UNITED STATES PATENT OFFICE

2,012,656

WHEELBARROW FOR COAL TRUCKS

James Bremner, Detroit, Mich.

Application October 16, 1933, Serial No. 693,760

3 Claims. (Cl. 280—52)

It is obviously a well known fact that the customary construction of wheel barrows provides the arrangement whereby a number of heads of the bolts used project through the metal bottom of the bed of the wheel barrow which causes thereby a decided obstruction to the use of the shovel in contact with the bed in the ordinary use of the same. For this reason the difficulty occasioned by this obstruction greatly retards the work of the operator, and in this manner and which is increased by the number of wheel barrows being employed, the delay resultant from this difficulty mounts to costly and useless expense for the coal dealer.

This difficulty is also very injurious to the edge of the shovel, as the same continuously contacting the bolt heads the edge becomes nicked and otherwise rendered rough and uneven.

The primary object of my invention is to incorporate certain features in the construction of this type of wheel barrow whereby the bolts of the construction are arranged so that their heads do not project through the bottom of the bed and are likewise not visibly within the bed, thereby effecting a perfectly smooth obstructionless surface, which admits of the rapid and uninterrupted operation of the shovel upon this surface.

It is needless to state that the difficulty caused by the obstructing bolt heads is entirely overcome as result of my improvement and discovery.

The invention possesses further advantages, all of which will be clearly revealed during the course of the following detailed description, illustrated throughout the accompanying drawings, and more fully pointed out in the appended claims.

With reference to the drawings, which illustrate in part:

Figure 1 is a side elevation of a typical wheel barrow for coal use and showing the invention fully embodied therein.

Figure 2 is a greatly enlarged sectional view of one of the principal channel members of the device.

Figure 3 is a top plan view of a portion of one of the channel members and clearly indicating the slotted opening therein adapted to receive the bolt head.

Figure 4 is a partial side elevation of a wheel barrow for coal, indicating a similar view of a modified form of my invention.

Figure 5 is a bottom or underneath view of the complete wheel barrow, indicating the invention thereupon.

Figure 6 is a transverse section taken substan-

tially upon line 6—6 of Figure 1, of the modified form of the invention.

Figure 7 is a partial bottom view of the wheel barrow indicating the modified form of the invention.

Preparatory to disclosing the invention in detail thereof, it is to be understood that throughout the disclosure the letters will refer to the various elements of the wheel barrow in coordination with the invention, while the numerals will designate the elements concerning the invention proper.

The invention comprises transversely arranged channel members indicated at 1, 2 and 3 respectively, and which are secured to bottom A of bed B in the spaced apart relation by means of preferably a welding process.

Openings 4 are provided in each of the channels 1, 2 and 3 so as to accommodate bolts 5 for channel 1, bolts 6 for channel 2 and bolts 7 for channel 3. All of said bolts have the usual nut and washer as indicated.

Referring to Figure 3 it is clearly observed that opening 4 in said channel members is provided with elongated slot 8, the purpose of which will be presently explained.

It is understood that channels 1 and 2 are permanently welded to bottom A, and with reference to Figure 1 it is seen that bolts 5 and 6 pass through blocks C and likewise through handle bars D and also retaining legs E to said bars respectively. Said channels being neatly recessed within blocks C as shown.

Inasmuch as channel members 1 and 2 are rigidly secured to bottom A and being transversely arranged, the advantage derived therefrom is that said bottom is greatly strengthened by this reinforcement, and for this reason the bottom will withstand much hard wear and abuse, and will give decidedly more service than the ordinary method of construction of this type of wheel barrow.

In Figure 1 it is clearly seen also that bolts 1 and 2 pass through blocks C and also through handle bars D, and in this manner body B is rigidly retained with said handle bars, effecting thereby a substantial construction.

The forward portion of body B is also substantially supported by virtue of vertically arranged braces 9, one end of which is secured to channel member 3 by means of bolts 7 respectively, and the opposite end thereof being secured to the forward portion of respective handle bars D by bolts 10 as indicated.

Again referring to Figure 3, the object of slot 55

8 of opening 4 is to permit the replacing of either of bolts 5, 6 and 7 with new bolts when same become corroded or otherwise unreliable. This arrangement being necessary in view of the permanent engagement of channel members 1, 2 and 3 with bottom A of body B. It is understood of course that said bolts are provided with a square neck which is adapted to engage slot 8 and remain in this relation until removed. To remove the 10 bolts the nut therefor is disengaged and the head of the bolt is shifted to opening 4, which is slightly larger than said head thereby permitting same to drop through the opening. The head of the new bolt is likewise inserted into said opening and 15 shifted so that the neck of the bolt will engage slot 8 and permanently remain therein.

Another advantage of the invention is the provision of gate 11, which is adapted to pivotally engage the forward portion of body B by means of 20 hinges 12, and it is understood that said gate will remain normally in a vertical position as indicated in Figure 1 because of spring 13, one end of which is secured to one side portion of said gate and the opposite end thereof being secured 25 to clip 14 which is connected to body B where shown.

The object of said gate is to prevent the coal from falling from the front end of the wheelbarrow, particularly when the coal is well piled 30 upon the same. Spring 13 admits of gate 11 being readily opened when required but will retain the gate normally closed.

While the primary intention of the invention is to provide means for eliminating the necessity of 35 having the bolts pass through bottom A, by providing channels as described, the invention seeks to cover any method where members are arranged transversely of body B and provided any form of recess to accommodate the bolt heads.

40 Referring particularly to Figures 4, 6 and 7, a modified form of the invention is illustrated. In this form the invention seeks to cover a longitudinally arranged method, which comprises metal U members 15 for the rear and 16 for the front. Said members are adapted to conform to blocks C 45 and handle bars D respectively and are secured to these members by bolts 17 with the usual nuts and washers therefor as shown. U members are preferably welded to bottom A of body B and the top portion of said members being neatly recessed into blocks C respectively. In this manner 50 the invention seeks to cover any method by longitudinal arrangement for this purpose.

Having thus described my invention, what I 55 claim as new is:

1. In a wheelbarrow, a pair of handle bars, a ground engaging wheel supported by the forward end portions of the handle bars, a body, blocks

arranged longitudinally on the handle bars, channel members extending transversely across the bottom of the body and being welded thereto, the upper edges of the blocks being notched to accommodate said channel members so that the upper faces of the blocks engage the bottom face of the body, leg members, bolts extending through the bottom of the channel members, blocks, handle bars and leg members respectively to secure the parts in a rigid assembled position, nuts 10 threaded on the lower ends of the bolts.

2. In a wheelbarrow, a pair of handle bars, a ground engaging wheel supported by the forward end portions of the handle bars, a body, blocks arranged longitudinally on the handle bars, channel members extending transversely across the bottom of the body and being welded thereto, the upper edges of the blocks being notched to accommodate said channel members so that the upper faces of the blocks engage the bottom face of 20 the body, leg members, bolts extending through the bottom of the channel members, blocks, handle bars and leg members respectively to secure the parts in a rigid assembled position, nuts threaded on the lower ends of the bolts, the base 25 of each channel member being formed with key-hole shaped openings to accommodate the headed upper ends of the bolts and to permit lateral and vertical shifting of the body when the bolts are to be replaced.

3. In a wheelbarrow, a pair of handle bars, a ground engaging wheel supported by the forward end portions of the handle bars, a body, blocks arranged longitudinally on the intermediate portions of the handle bars, channel members extending transversely across the bottom of the body and being welded thereto at the intermediate portion and rear portion thereof, respectively, the upper edges of the blocks being notched to accommodate said channel members so that the upper faces of the blocks engage the bottom face of the body, leg members, bolts extending through the bottom of the channel members, blocks, handle bars and leg members respectively to secure the parts in a rigid assembled position, nuts threaded on the lower ends of the bolts, an additional channel member welded transversely to the bottom of the forward end portion of the body, vertically disposed braces secured at their lower ends to the forward ends of the respective handle bars, the upper ends of the braces being disposed laterally for disposition against the bottom of the front channel member, and securing means extending through the base of the front channel member and the laterally disposed upper ends of the braces.

JAMES BREMNER.
